MEDICINAL COMPOSITIONS

Jacob Osterweil, 1001 Jerome Ave., Bronx 52, N.Y.
No Drawing. Filed Nov. 15, 1961, Ser. No. 152,618
9 Claims. (Cl. 167—65)

This invention is a novel composition of matter having antispasmodic, sedative and hypnotic action.

There are known proprietary sedative and hypnotic compositions which contain a sedative agent or an anti-histamine agent, generally in combination with an antispasmodic compound such as scopolamine or like alkaloid. The antispasmodic is for the purpose of controlling the muscular and nervous tension which often accompanies insomnia and other conditions in which a sedative medicine is indicated. Such compositions containing scopolamine are potentially dangerous in causing untoward side reactions or toxic manifestations, of which dizziness, disturbed co-ordination, dryness of the mouth, palpitation, and blurring of the vision may be cited as illustrative, and such compositions carry strict warnings to discontinue their use in the event symptoms of the above nature are observed.

It is an object of this invention to provide an effective antispasmodic which is safe and may be used alone or in combination with sedative and analgesics.

It is a further object of the present invention to provide a novel medicinal composition which is effective as a sedative and hypnotic and which is so safe in its action that no caution label is needed.

An additional object of this invention is to provide a potentiated composition wherein the desired therapeutic activity is obtained with minimal dosage.

It has now been found that *Euphorbia pilulifera*, an antispasmodic of long standing, may be used in combination with para aminobenzoic acid to provide a safe, effective anti-spasmodic in dosages one-tenth of normal. The U.S. Dispensatory, 25th edition, 1955, describes *Euphorbia* as having an active principle which is irritating to the stomach in large doses. The former official dose, National Formulary VII, was stated to be about 30 grains of the dried drug. It is commercially available as powdered extracts wherein one part represents four or five parts of the dried drug. Pillular and fluid extracts are also available. As a result of its tendency to produce gastritis *Euphorbia* has fallen into more or less disuse but the present invention makes it possible to obtain the desired antispasmodic action of *Euphorbia* without the likelihood of producing stomach irritation. By using para aminobenzoic acid in approximately 100% to 200% by weight of the *Euphorbia*, the dose of the *Euphorbia* may be reduced to $\frac{1}{10}$ its normal value without loss of efficacy. For example a combination of $\frac{3}{4}$ grain of the powdered extract of *Euphorbia* (4:1) with 1 grain of para aminobenzoic acid exhibits the approximate effect of 7.5 grains of the powdered extract without gastric irritation.

There is thus provided a safe, efficacious antispasmodic which may advantageously be combined with other ingredients such as sedatives, analgesics and antihistamines. Sedative compounds include the barbiturates, codeine, morphine, chloral hydrate, bromisovalum, acetylcarbromal, bromides such as ammonium bromide, and various vegetable drugs such as *Passiflora incarnata*, etc. Analgesics include those of the benzene series such as salicylamide, aspirin, acetanilide, phenacetin; the salicylates such as sodium salicylate; phenyl cinchonate; and similar compounds having like physiological activity. Antihistamine compounds include pyrilamine maleate,* methapyrilene hydrochloride,* chlorpheniramine maleate

2

(U.S.P.), clemizole hydrochloride (1-p-chlorobenzyl-2-pyrrolidyl-methyl benzimidazole HCl), thonzylamine hydrochloride,* tripeleannamine citrate,* meclizine hydrochloride (New and Nonofficial Drugs 1960), and cyclizine hydrochloride, etc. A particularly effective and advantageous medication for sedation and hypnotic action results from the combination of the four ingredients; powdered extract of *Euphorbia*, powdered extract of *Passiflora*, salicylamide and para aminobenzoic acid.

5 10 15

The inclusion of the para aminobenzoic acid in such a combination potentiates the sedative and hypnotic action of the other components to an extent not expected from a knowledge of their properties. Examples illustrative of the practice of this invention are given below wherein one part of the extracts represents four parts of the dried drug.

Example 1

		Extra Grains
20	Powdered extract of <i>Euphorbia pilulifera</i>	0.75
	Para aminobenzoic acid	1.00

Example 2

25	Powdered extract of <i>Euphorbia</i>	1
	Para aminobenzoic acid	1

Example 3

30	Powdered extract of <i>Euphorbia</i>	1
	Para aminobenzoic acid	2

Example 4

	Powdered extract <i>Euphorbia</i>	0.75
	Codeine sulfate	0.25
	Para aminobenzoic acid	1.00

Example 5

	Powdered extract <i>Euphorbia</i>	.75
	Phenobarbital	.25
	Para aminobenzoic acid	1.00

Example 6

	Powdered extract <i>Euphorbia</i>	.75
	Powdered extract <i>Passiflora incarnata</i>	.75
	Para aminobenzoic acid	1.00

Example 7

	Powdered extract <i>Euphorbia</i>	0.75
	Aspirin	3.00
	Para aminobenzoic acid	1.00

Example 8

	Powdered extract <i>Euphorbia</i>	0.75
	Salicylamide	3.00
	Para aminobenzoic acid	1.00

Example 9

	Powdered extract <i>Euphorbia</i>	0.75
	Salicylamide	3.00
	Powdered extract <i>Passiflora</i>	0.75
	Para aminobenzoic acid	1.00

Example 10

	Powdered extract <i>Euphorbia</i>	0.75
	Salicylamide	3.00
	Methapyrilene hydrochloride	0.38
	Para aminobenzoic acid	1.00

Example 11

	Powdered extract <i>Euphorbia</i>	0.75
	Salicylamide	3.00
	Powdered extract <i>Passiflora</i>	0.75
	Methapyrilene hydrochloride	0.38
	Para aminobenzoic acid	1.00

* See Merck Index, 6th ed.

Compositions may be prepared where the vegetable drugs are used in their equivalent forms such as the fluid extract or tincture, when such would be more desirable than the powdered extract. The compositions may also be made in various dosage forms such as tablets, capsules, or liquids utilizing the usual pharmaceutical carriers known to the art. They may be safely used for insomnia, nervous tension, asthma, and in other conditions where antispasmodic, sedative and hypnotic action is desirable.

What is claimed is:

1. A therapeutic composition comprising an extract of *Euphorbia pilulifera* and para aminobenzoic acid in therapeutically active quantities in a pharmaceutical carrier whereby the dose of the Euphorbia is reduced to one-tenth of its dose when used without the para aminobenzoic acid.

2. A therapeutic composition comprising an extract of *Euphorbia pilulifera* and para aminobenzoic acid in therapeutically active quantities where the latter is present in the range of 100% to 200% by weight of the former in a pharmaceutical carrier.

3. A therapeutic composition comprising a sedative, an extract of *Euphorbia pilulifera* and para aminobenzoic acid in therapeutically active quantities in a pharmaceutical carrier whereby the dose of the Euphorbia is reduced to one-tenth of its dose when used without the para aminobenzoic acid.

4. A therapeutic composition comprising an extract of *Passiflora incarnata*, an extract of *Euphorbia pilulifera* and para aminobenzoic acid in therapeutically active quantities in a pharmaceutical carrier whereby the dose of the Euphorbia is reduced to one-tenth of its dose when used without the para aminobenzoic acid.

5. A therapeutic composition comprising an extract of *Passiflora incarnata*, an extract of *Euphorbia pilulifera*

and para aminobenzoic acid in therapeutically active quantities where the latter is present to the extent of 100% to 200% by weight of the Euphorbia in a pharmaceutical carrier.

6. A therapeutic composition comprising a sedative, an analgesic of the benzene series, an extract of *Euphorbia pilulifera* and para aminobenzoic acid in therapeutically active quantities in a pharmaceutical carrier whereby the dose of the Euphorbia is reduced to one-tenth of its dose when used without the para aminobenzoic acid.

7. A therapeutic composition comprising a sedative, salicylamide, an extract of *Euphorbia pilulifera* and para aminobenzoic acid in therapeutically active quantities in a pharmaceutical carrier whereby the dose of the Euphorbia is reduced to one-tenth of its dose when used without the para aminobenzoic acid.

8. A therapeutic composition comprising an extract of *Passiflora incarnata*, salicylamide, an extract of *Euphorbia pilulifera* and para aminobenzoic acid in therapeutically active quantities in a pharmaceutical carrier whereby the dose of the Euphorbia is reduced to one-tenth of its dose when used without the para aminobenzoic acid.

9. A therapeutic composition for insomnia comprising the following ingredients in the ratio: powdered extract *Passiflora incarnata* $\frac{3}{4}$ grain; salicylamide 3 grains; powdered extract *Euphorbia pilulifera* $\frac{3}{4}$ grain; and para aminobenzoic acid 1 grain in a pharmaceutical carrier.

UNITED STATES PATENT OFFICE
CERTIFICATE OF CORRECTION

Patent No. 3,117,910

January 14, 1964

Jacob Osterweil

It is hereby certified that error appears in the above numbered patent requiring correction and that the said Letters Patent should read as corrected below.

Column 2, line 18, strike out "Extra".

Signed and sealed this 16th day of June 1964.
